INVENTOR

VERNON S. ELLZEY
Eric Schlinger, ATTORNEY

UNITED STATES PATENT OFFICE

VERNON S. ELLZEY, OF ROCHESTER, NEW YORK

COMB

Application filed December 22, 1930. Serial No. 503,996.

This invention relates to combs for use in the treatment and preparation of the hair prior to waving it and the object of this invention is to provide such a comb with means whereby the hair lotion or wave set may be easily and quickly applied to the hair.

Another object of this invention is to so construct the comb that a reservoir for storing a quantity of the lotion may be attached thereto and the lotion fed from this reservoir and directed to the base of the teeth of the comb.

Another object of this invention is to provide novel means for controlling the flow of the lotion from the reservoir.

Other objects and attendant advantages will become more readily apparent from the detailed description of one embodiment of my invention which follows, reference being had to the accompanying drawings in which

Figure 1 is a side elevation of the comb and reservoir provided thereon.

Figure 2 is an end elevation thereof.

Figure 3 is a vertical sectional view taken on the line 3x-3x of Figure 1.

Figure 4 is a vertical sectional view taken on the line 4x-4x of Figure 1 looking in the direction of the arrow.

Figure 5 is a horizontal sectional view taken on the line 5x-5x of Figure 1.

In the several figures of the drawings, like reference numerals indicate like parts.

The improved comb with its reservoir forming the subject matter of my present invention is especially adapted for use by hair dressers when applying hair wave lotions or wave sets to the hair.

As illustrated in the figures of the drawings the comb is preferably a double comb with coarse teeth 1, 1 provided on one side and finer teeth 2, 2 provided on the other side. The central portion of the comb between these teeth is formed into a semi-circular channel 3 and in this channel is partially embedded the tubular reservoir 4. A suitable strap 5 at the front of the comb and another strap 6 near the rear of it, firmly holds the reservoir in place in the semi-circular channel in the middle of the side of the comb.

The reservoir has a filling cap 7 at the

front end which when removed permits the filling of the reservoir. The lotion passes out of the reservoir thru a series of holes 8, 8 provided in the wall thereof. These holes are in line with the vertical grooves 9, 9 provided between the inner ends of the coarse teeth 1, 1. In this way the lotion flows directly from the reservoir thru the grooves, 9, 9 onto the strands of hair located between the teeth 1, 1.

To control the flow of the lotion from the reservoir to the hair, a cylindrical valve 10 is rotatably mounted within the reservoir 4. This valve is provided with a series of holes 11, 11 which are brought in alignment with the holes 8, 8 of the reservoir when the valve is turned to a predetermined angular position with relation to the reservoir. For this purpose the valve 10 is provided with a valve stem 12 at the inner end of it and this valve stem passes thru the sleeve 13 which is threaded into the inner end of the reservoir 4. On the outside of the reservoir the valve stem 12 has the head 14 formed thereon to which the handle 15 is attached. This handle projects laterally from the head to permit the rotation of the valve by means of it.

In the end of the sleeve 13 are provided two grooves 16, 16 suitably spaced apart from each other and by turning the handle 15 to engage into either the one or the other of these grooves, the holes in the valve are either held in alignment or out of alignment with the holes in the reservoir. As illustrated in the figures of the drawings the holes in the valve 10 are in line with the holes in the reservoir when the handle 15 is in the horizontal position illustrated in dotted lines in Figure 4 so that in this position of the handle the lotion is free to flow from the reservoir to the hair. To stop the flow of the lotion from the reservoir, the handle 15 is turned from this position to the vertical downward position illustrated in Figure 1 because the movement of the handle into this position moves the holes in the valve out of alignment with the holes in the reservoir.

In order to hold the handle of the valve yieldingly in place in either the one or the other of the two grooves 16 provided in the

end of the sleeve, an expansion spring 17 is placed between the sleeve 13 and the end of the valve 10 on the inside of the reservoir as illustrated in Figure 5.

5 I claim:

1. A comb having a longitudinal channel provided therein, teeth projecting from the edge of said longitudinal channel with grooves provided between the inner ends of 10 said teeth and leading out of said channel, a reservoir located in said channel, said reservoir having outlet openings therein in line with the grooves between said teeth and controlling means for controlling the flow of 15 liquid from the reservoir into said grooves.
2. A comb having a longitudinal channel provided in the side thereof, teeth projecting from the edge of said channel with grooves provided between the inner ends of said teeth 20 and leading out of said channel, a reservoir mounted in said channel, said reservoir having outlet openings therein in line with said grooves between said teeth, a valve rotatably mounted within said reservoir, said valve 25 having valve openings therein corresponding to the outlet openings in said reservoir, a valve stem at one end of said valve, a handle provided on said valve stem, means provided at the inner end of said reservoir to 30 hold said handle in a predetermined position and yielding means for holding said handle in said position.

VERNON S. ELLZEY.
